(57) **CLAIM**

The ornamental design for a vertical maze as shown and described.

DESCRIPTION

FIG. 1 is a perspective view of a vertical maze according to our new design;

FIG. 2 is a front elevation view thereof;

FIG. 3 is a right-side perspective view thereof; and,

FIG. 4 is a left-side perspective view thereof.

The internal structures of the vertical maze, illustrated in a contrasting light gray, form no part of the claimed design.
